UNITED STATES PATENT OFFICE.

GLENN H. CURTISS, OF HAMMONDSPORT, NEW YORK, ASSIGNOR TO CURTISS AERO-
PLANE & MOTOR CORPORATION, A CORPORATION OF NEW YORK.

FLYING-MACHINE.

1,204,380.

Specification of Letters Patent.

Patented Nov. 7, 1916.

Application filed June 23, 1910. Serial No. 568,425.

To all whom it may concern:

Be it known that I, GLENN H. CURTISS, a citizen of the United States, residing at Hammondsport, New York, have invented 5 certain new and useful Improvements in Flying-Machines, of which the following is a clear, full, and exact description.

My invention relates to a flying machine and is particularly applicable to an aero- 10 plane or heavier-than-air machine, and it consists of certain novel parts and combinations of parts specified in the claims concluding these specifications.

My invention may be embodied in a variety of forms, but in the drawings I have 15 illustrated as embodiments thereof those forms which I now prefer.

In the forms illustrated in the drawings, Figure 1 is a side view of a flying machine 20 of the Curtiss type,—parts which are immaterial to the present invention being omitted, such as the rear vertical rudder and the front horizontal rudder. The balancing surfaces are shown as moved to their 25 equilibrium-restoring position; Fig. 2 is a sectional view on the line 2—2 of Fig. 1 looking in the direction of the arrow just above the upper main supporting surface 1; Fig. 3 is an enlarged top plan view of 30 the shoulder frame and equalizing device; Fig. 4 is an enlarged detail of the balancing surfaces, showing how they may shift without changing the angle between them; Fig. 5 is an enlarged front elevation of the 35 shoulder frame and equalizing device of Fig. 2 if the balancing surfaces shift from the dotted-line to the full-line positions shown in Fig. 4; Fig. 6 is a detail of a modification; and Fig. 7 is a rear view similar to Fig. 2 but showing a further modified arrangement.

The machine shown is a heavier-than-air machine of the biplane type, 1 and 2 being the upper and lower main supporting surfaces. The balancing surfaces are preferably 45 independent of the main supporting surfaces, and are shown as two similar flat ailerons 3 and 4, one at each side of the machine, and pivoted at 3° and 4° to the connecting 50 struts 5, 5, between the two main supporting surfaces.

6 and 7 are supports which hold the front and rear rudders respectively and which it is not necessary to illustrate.

9 is the seat for the operator. 55 X, in Figs. 1 and 4, represents the normal rush of air toward the machine.

In the embodiment shown in the drawings, when lateral equilibrium is lost and it is desired to tilt the machine back to 60 normal horizontal, the balancing surface at the depressed side is thrown down so that the rush of air strikes it at a positive angle of incidence in order to create a lifting effect on that side, and the other balancing 65 surface thrown up to a negative angle to create a depressing effect. In my machines up to this time this has been done by the operator, and although I do not limit myself to movement thereof by the operator, I prefer 70 to move the balancing surfaces in this way, and have so illustrated my invention in the drawings. As one means of simultaneously presenting and holding the balancing surfaces at opposite angles of incidence, I have provided a movable shoulder frame 8 which incloses the operator's shoulders and which operates the wires 11, 11^a, 75 12 and 12^a, which run over stationary pulleys 13 to 26 and are attached to the rear 80 edges of the balancing surfaces. The shoulder frame is connected to the seat 9 by rods or bars 10, which are pivoted at 10° and 10^b, and the wires are preferably so arranged 85 that when the operator leans toward the 85 uptilted side of the machine, the balancing surfaces will be thrown in opposite directions so as to present them at opposite angles of incidence, with the one on the depressed side at a negative angle, and the one on the elevated side at a positive angle. 90 This will accomplish the restoration of equilibrium.

In order to insure exactly equal resistance to the forward movement of the machine at the opposite sides under the various conditions of operation, I preferably employ pressure equalizers which are, in the embodiment illustrated, attached to the wires operating the ailerons, which equalizers may be of any suitable construction, such, for example, as the whiffletrees 27, 28 shown in Figs. 2 and 5, or the single whiffletree 31 shown in Fig. 7, or the pulleys 27^a, 28^a shown in Fig. 6. It will be observed that 105 in either case, with the construction and arrangement of parts shown, the ailerons will, when idle (before the shoulder frame is

moved) always be in the stream line and therefore wholly inactive; and that when they are operated in balancing the machine the retarding force exerted by the aileron on one side of the machine acts through a whiffletree or pulley, or other suitable equalizing device, directly opposed to the retarding force exerted by the aileron on the other side of the machine, so that these forces must 10 always be exactly equal, since, should from any cause a tendency to inequality exist by reason of the ailerons presenting unequal angles of incidence to the air, the whiffletree or pulley will turn sufficiently to permit 15 the ailerons at the two sides to shift slightly in the same angular direction until they present exactly equal angles of incidence to the air and, hence, to prevent any possible turning tendency of the machine around a vertical axis, even such as would be negligible and imperceptible in the operation of the machine.

I am aware that many variations of construction may be made without departing 25 from the spirit of my invention as claimed, and I therefore do not limit myself to the construction heretofore described and illustrated in the drawings.

What I claim is—

30 1. A flying machine comprising a balancing surface at each side thereof the angle of incidence of which may be varied, a two-part connection for operating said surfaces, an equalizing member interpolated in the 35 connection for moving one of said surfaces up and the other down, a second equalizing member interpolated in the connection for moving said first mentioned surface down and the other up, said members being capable of their 40 equalizing motion in response to varied air pressure on said surfaces so that said surfaces may move in the same direction, and means for bodily moving said

members in the same direction to move said surfaces in opposite directions. 45

2. A flying machine comprising a balancing surface at each side thereof the angle of incidence of which may be varied and which is pivoted forward of its center of pressure, a two-part flexible connection for 50 operating said surfaces, an equalizing member interpolated in the connection for moving one of said surfaces up and the other down, a second equalizing member interpolated in the connection for moving said first 55 mentioned surface down and the other up, said members being free for equalizing motion in response to varied air pressure on said surfaces, and common means for moving said members bodily in a predetermined 60 direction to move said surfaces in opposite directions.

3. A flying machine comprising a balancing surface at each side thereof, the angle of incidence of which may be varied, a flexible two-part connection for operating said surfaces, a pivoted equalizing member interpolated in said connection for moving one of said surfaces up and the other down, a second pivoted equalizing member interpolated in said connection for moving said first 65 mentioned surface down and the other up, said members being capable of their equalizing motion in response to varied air pressure on said surfaces so that said surfaces 70 may move in the same direction and said members oppositely, and common means for bodily moving said members in the same direction to move said surfaces in opposite 75 directions. 80

Signed at Chicago, Illinois, this 20th day of June A. D. 1910.

GLENN H. CURTISS.
